UNITED STATES PATENT OFFICE.

CARL HOLMSTRÖM AND PER NORDENFELT, OF WESTMINSTER, ENGLAND,
ASSIGNORS TO THE MAXIM-NORDENFELT GUNS AND AMMUNITION COMPANY, (LIMITED,) OF SAME PLACE.

QUICK-FIRING GUN.

SPECIFICATION forming part of Letters Patent No. 427,081, dated May 6, 1890.

Application filed January 7, 1890. Serial No. 336,175. (No model.)

To all whom it may concern:

Be it known that we, CARL HOLMSTRÖM and PER NORDENFELT, civil engineers, subjects of the King of Sweden, both residing at 32 Victoria Street, in the city of Westminster, England, have invented certain new and useful Improvements in Quick-Firing Guns, of which the following is a specification.

This invention has for its object a quick-firing gun suitable for semi-automatic working.

The breech part of a gun constructed in accordance with the invention is represented by the annexed drawings.

15 Figure 1 is a longitudinal section with the breech closed. Fig. 2 is a longitudinal section with the breech open, and Fig. 3 is a plan with the breech closed.

The portions marked *a* are the barrel and 20 parts formed therewith. The breech of the gun is closed by a breech-block *b*, which slides in a transverse opening or recess *a'* along suitable slightly-inclined guides. The breech-block receives its movement from a trans- 25 verse axis *c* upon the gun, and in semi-automatic working the axis receives motion from apparatus connecting it with the cradle or frame along which the gun recoils. This apparatus forms no part of the present invention. 30 Any convenient gear may be employed which rotates the axis against the resistance of a spring while the gun moves forward upon the cradle and sets the axis free at the end of the forward movement. For hand- 35 working the axis *c* may be turned by means of a hand-lever at its end. The axis has two arms *c' c'* projecting up into the breech-recess, one on either side of the breech-block, and these arms are connected by a pin *d* 40 passing through the breech-block from side to side. The hole in the breech-block by which the pin passes is elongated and so formed that the first movement of the arms in opening the breech takes place without 45 moving the breech-block, but in their further movement the arms carry the breech-block with them.

The breech-block is provided with a firing-pin *e*, and in this pin there is a transverse

elongated hole. A screw *f*, passing through 50 the hole and fixed in the breech-block, limits the movement of the firing-pin. A coiled spring *g* presses the firing-pin rearward. The spring *g* is kept in place by a steel bushing *b'* let into the front of the breech-block. 55 *b'* is a locking-pin.

The nose of the firing-pin projects, as shown, through a central hole in the bushing *b'*, and so reaches the priming of the cartridge, which is shown at *h*. At the time of firing the pin 60 is thrown forward in opposition to this spring by the blow of a hammer *i*. This hammer is contained in the breech-block. It is mounted on a transverse axis *i'* near the lower part of the block and toward the front thereof. 65

In the breech-block, in front of the hammer-axis and below it, there is a trigger-axis *k*, and on this axis two sears *l* and *m* are mounted. One, the trigger-sear *l*, is fixed upon the axis, and the other or safety sear *m* is movable 70 around it. The trigger-axis also carries a trigger-arm *n*, projecting rearward, and this arm at the time of firing is operated upon by trigger mechanism carried by the cradle or frame in which the gun is held. Within the 75 breech-block also, and at the lower part, there is a mainspring. The upper limb *o* of this spring presses upon the foot of the hammer and throws the hammer forward when it is released. The lower arm of the mainspring 80 is forked, and one of its ends *o'* presses upward upon the trigger-sear *l* and causes it to engage with a dent *i'* upon the foot of the hammer. The other extremity *o'* of the main- 85 spring presses downward upon an arm of the safety-sear *m*, and thereby gives to the sear-nose a rearward tendency, and causes it to engage, when free to do so, with a dent *i''* upon the hammer in front of its axis.

The gun is provided with a two-armed extactor *p*, mounted upon a transverse axis *p'* upon the gun. The extactor-arms have at their upper ends lips which engage with the flange of the cartridge. The arms are so formed that they project in rear of the axis, 95 and these projections *p''* are struck by studs *b''*, formed upon the breech-block, as the breech-block comes to the end of its course

in opening. There are also studs p^3 upon the arms of the extractor, which enter recesses b^4 in the upper part of the breech-block, and serve to retain the breech-block and prevent the breech closing until the cartridge is inserted.

The action, then, of the apparatus is as follows: In semi-automatic working the mechanism connecting the gun with the cradle 10 turns the principal axis c and so opens the breech at the time when the gun moves forward after recoil. At this time a spring also is constrained, which at the end of the forward movement tends to rotate the axis in the 15 contrary direction. Before the breech opens the transverse pin d , by which the block is moved, presses against the foot of the hammer i , compressing the mainspring and carrying the head of the hammer back away from 20 the firing-pin. When the hammer is thus cocked, the sears l and m fall in and prevent its return. During the opening of the breech the studs b^3 upon the breech-block 25 strike upon the extractor p and cause it to withdraw the case of the cartridge last fired from the chamber of the gun, and this case is projected rearward out of the gun. As soon as the breech is fully open the breech-block b , in semi-automatic working immediately 30 commences to return, but it is caught and prevented from doing so by the studs p^3 upon the extractor which engage with it. The breech-block is thus held until another cartridge as it enters the gun displaces the 35 extractor and then immediately the breech-block returns and closes the breech behind the cartridge. At the moment of closing the trigger sear l releases the hammer, being moved away by means of the trigger mechanism 40 operating on the arm n , and the hammer is then only retained by the safety-sear. By further movement of the transverse pin d this comes against a prolongation of the safety-sear m , and throws it out of its dent 45 and then the gun fires.

When firing with trigger, the trigger mechanism is set so as not to cause the arm n to be moved automatically in closing. The transverse pin, after the breech is fully closed, releases the hammer from the safety-sear, and 50

the hammer remains retained by the trigger-sear, which has to be displaced before firing.

What we claim is—

1. The mechanism consisting of the barrel part a , the breech-block b , the transverse horizontal axis c beneath the barrel part, the arms c' on the axis c , the pin d , carried by the arms c' and passing through the breech-block, the firing-pin e and the hammer i on the axis i' contained in the breech-block, the sear m , engaging with the hammer, and the whole so arranged that the pin d operates upon the hammer in opening the breech to bring it to the cocked position, and upon the sear m in closing the breech to release the hammer. 55

2. The mechanism consisting of the barrel part a , the breech-block b , the transverse horizontal axis c below the barrel part, the arms c' on the axis c , the pin d , carried by the arms c' and passing through the breech-block, the firing-pin e , the hammer i on the axis i' contained in the breech-block, the sear m , engaging with the hammer, the trigger-sear l , and its lever n , substantially as set 75 forth.

3. In combination with the aforesaid mechanism, the extracting and retaining mechanism, consisting of the extractor p , with lips engaging with the flange of the cartridge, the parts b^3 on the breech-block which strike the extractor and so cause it to operate, and the parts p^3 on the extractor which engage with the breech-block and prevent the breech closing until a cartridge is inserted. 85

4. The firing mechanism consisting of the breech-block b , the firing-pin e , having an elongated hole through it, the pin f , passing through the said hole and fixed in the breech-block, the spring g , and the hammer i .
